UNITED STATES PATENT OFFICE

2,168,783

FLOW BOOSTER FOR AIR PIPES

Joseph Eucier, Philadelphia, Pa.

Application February 4, 1936, Serial No. 62,262

4 Claims. (Cl. 98—38)

This invention relates to flow boosters for air pipes.

In the use of hot air furnaces it is difficult at times, to heat certain rooms in a house, where the cause is the slowness at which the hot air from the upper chamber of a hot air furnace flows through the hot air pipe to the room.

Sometimes a motor fan is used in connection with a hot air pipe to increase or boost the velocity of air flowing in the pipe. The operation of such a motor fan is a constant added expense to the running of a hot air system, where the air in the pipes must be forced by a fan to get the proper flow of hot air desired.

15. The main object of my invention is to provide a stationary booster device adapted to be fitted in the line of pipe carrying hot air, so constructed that, without the aid of a motor fan it will cause a practical increase in the flow of hot air flowing through the hot air pipe and through the booster device, in line with the path of air flowing in the pipe, while at the same time taking in extra air surrounding the booster device, and increasing the volume of air flowing in the 25. pipe beyond the booster device.

Another object of my invention is to have booster device so located, when used in connection with a hot air furnace, that it will be in the path of the cylinder of rising air, immediately 30. surrounding the furnace.

With these and other objects, which will hereinafter appear, my invention resides in certain constructions, one embodiment of which is illustrated in the drawing and is hereinafter described. The operation is explained and what I claim is set forth.

In the drawing,

Figure 1 is a sectional elevation of a fragment of the upper portion of a hot air furnace and an air pipe showing the attachment thereto, of the various parts, of my invention.

Figure 2 is a sectional elevation of another fragment of the upper portion of a hot air furnace and air pipes, including a modified form of 45. my invention.

Figure 3 is a vertical longitudinal section taken on the line 3—3, of Figure 4, showing the booster.

Figure 4 is an end elevation, looking into the intake end of the booster, shown in Figures 50. 1 and 2.

In the figures, the upper casing portion 10, of a furnace, is shown in each of the Figures 1 and 2 to have hot air pipes 11 and 12, leading from the uppermost, hot air chamber 13. The holes 55. 14 and 15 are for hot air pipe connections.

Mounted upon the top of the furnace casing, and spaced from the inclined wall 16, is a hood 17. In Figure 2, openings 18 are located just above the section 19, of the pipe 11. The hood 17 is closed all around at the top 20 and serves as a 5 kind of air jacket, surrounding the wall 16, to retain the heat radiating from the air chamber 13. The skirt 21, of the hood 17, serves also, by its spacing from the casing portion 10, to catch a part of the heated air rising next to the vertical 10 wall of the furnace.

In the line of each of the air pipes 11 and 12, is a section which constitutes the booster 22. (See also Figures 3 and 4.) This booster 22 has a tubular portion 23, of the same size as the pipes 15. 11 and 12, and is fitted at each end to portions of the pipe to which it is attached. This tubular portion 23, has a zone of holes 24 therethrough. The holes 24 are shown to vary in size, the smaller 20 holes being at the upper part of the tubular portion 23, and the larger ones being at the bottom part, so that most of the air drawn into the portion 23, comes in through the lower and larger holes, where the upwardly traveling warm air, next to the furnace, is more easily entered, in the 25. direction of its movement, however the influence of the suction operates to draw some air into all of the holes. Surrounding the holes 24 on the outside, is a tapered thin flange 25, fixed at 26, to the booster portion 23, and diverging toward the 30. furnace to afford an opening 27, to catch and lead air into the holes 24, where it is drawn in.

Within the booster portion 23, is fixed the sheet metal truncated conical piece 28, positioned to have its small end away from the furnace and 35. positioned to be opposite the holes 24. This piece 28 fits at 29 into the portion 23, at a plane back of the holes 24, toward the furnace. Projecting through the mouth or small end 30, of the piece 28, is a double conical element 31, having its axis 40. preferably co-incident with the axis of the piece 28, which is also the axis of the cylindrical portion 23. The cone portion 32 is within the piece 28, while the cone portion 33 extends beyond the mouth end 30, of the piece 28. The tapered piece 45. 31 is supported in position by the thin arms 34, having their broad sides in planes passing through the axis of the booster.

Extending from the upper edge of the tapered, outside flange 25, to the hood 17, just over the 50. holes 18, is the cover piece 35, open below. The air pipe 12 is shown to have a booster like the booster 22, on pipe 11; similar parts being similarly numbered, respectively. If desired, for reducing the expense of installation, the hood 17 55.

and the cover piece 35 can be left off, and the booster 22 alone used, without these auxiliary parts, as the booster will operate by itself without them. Some saving in heat may be had by adding the hood 17 and the cover piece 35.

Having described the construction of the one embodiment of my invention above described and illustrated in the drawing, I will now explain its operation.

When air, water or any other fluid flows at a certain rate through a pipe and into a conical, convergent, tubular element, the fluid flows out of the small end of such an element at a much increased velocity. The nozzle on the end of a hose is such an element, giving such force to the water in increased velocity, as to throw the water considerable distance. This increased velocity of the fluid emerging from the conical element produces another effect, and that is to reduce the side pressure of the fluid, next to the stream, just emerging from the small end of the conical element. The effect of this reduction of pressure in a booster including an outside tube, having a conical shell within, and holes in the wall of the tube near the conical shell, is to produce a suction through the holes. In the case where air is the fluid considered, heated air flowing in a hot air pipe of a furnace, as the pipe 11, and using the booster 22, the velocity of the air flowing from the pipe section 19, into the conical piece 28, of the booster 22, is greatly increased as it leaves the mouth end 30, of the piece 28, and produces a suction within the booster 22, drawing in air through the holes 24, to join circumferentially the faster flowing stream of air, leaving the mouth end 30, so that both the velocity and volume of air flowing in the portion of the pipe 11, is increased beyond the booster 22, through the remaining part of the pipe 11, to a register at the end of this pipe 11, (not shown) into a room. This increase in volume and velocity of hot air, flowing from the register, gives the air within the pipe 11, beyond the booster, less chance to lose its heat by radiation from the pipe, on the way to the register, because a given quantity of hot air, flowing in the pipe 11, remains a much shorter time within the pipe 11. It is evident that while the tapered piece 31, thus increases the velocity of flow of air leaving the mouth end 30, of the booster 22, the booster will operate and perform its functions if this piece 31 were eliminated. By actual use of such a booster, as 22, illustrated in the drawing and attached to a furnace pipe, as 11 or 12, I have heated rooms that could not be heated before. Considering the function of the outside conical flange 25, this acts to guide outside air to the holes 24, as well as to shut off any draft of air, over the outside of the holes 24.

By having the holes 24, larger at the bottom of the portion 23, than at the top, I take advantage of the upward natural flow of air coming up from the hot sides of the furnace. However regardless of the relative size of the holes 24, the air surrounding the holes 24 will be drawn in. By positioning the booster 22 near the furnace, as I have, the air entering the booster 22, from the pipe section 19, is hotter than it would be at a greater distance from the furnace. The hotter this air, entering the booster 22, the hotter will be the air leaving it at a much increased velocity, besides the cylinder of rising air, next to furnace is hotter than air further away, making for an evident advantage in drawing in hotter air through the holes. In order to take further advantage of the heat radiated from the furnace,

particularly at its top next to the upper hot air chamber, I provide the hood 17, as an air jacket, having outlets at the top, as at 18, from which outlets 18, the extra heated air finds its way beneath the cover 35, to the booster 22, at the flange 25. This cover 35 being open below, will catch heated air of the rising cylinder of air, immediately adjacent the furnace, and convey it to the booster. This air jacket or hood being open around the furnace, at the skirt 21, lets in hot air coming up from contact with the furnace. This air jacket 17 also serves as a kind of heat insulator about the walls 16, of the uppermost hot air chamber 13, from which the hot air enters the hot air pipes, radiating therefrom, as pipes 11 and 12. The booster 22 will operate independent of any hood 17 and cover 35, as auxiliary means. The booster 22 will also operate at a comparatively further distance, or near the furnace, as shown in the drawing. The booster will also operate in the line of any air pipe, where the air entering the booster from such pipe has an initial velocity, however produced; as by fan or otherwise, in connection with an air conditioning device giving the air flowing axially into the booster, an initial velocity. Air entering the holes 24, can be treated air as to humidity, or heat, or cold, or any combination thereof.

Inasmuch as modifications of the structure of the booster and other features of my invention can be made without departing from the spirit and scope of my invention, I wish to include all forms which come within the purview of the following claims.

I claim:

1. In an air flow device adapted to operate in connection with the natural flow of heated air in a hot air pipe of a hot air furnace or the like, stationary means for increasing said natural flow of heated air in an unobstructed, central zone of said hot air pipe beyond said means, said stationary means comprising a tubular body forming a continuous section of said hot air pipe, a truncated cone member positioned to have its large end fitting into the bore of said tubular body to be further positioned substantially co-axially therewith and to have its large end in free and unobstructed receiving position, to receive a full section of hot air from said hot air pipe, and with its small end positioned to discharge a central zone of hot air into a continuing length of said hot air pipe in the line of its natural flow, to increase its lineal velocity at said central zone there being openings in that zone of said tubular body, surrounding said conical member beyond its large end, whereby free air surrounding said zone of openings, is drawn into said tubular body to mix with heated air flowing in a central zone from the small end of said conical member.

2. In an air flow device having a stationary means made in accordance with that mentioned in claim 1, and having in addition a radially projecting flange about said flow means, positioned to surround said conical member.

3. An air flow device adapted to increase the flow of heated air beyond its natural flow in a hot air pipe, of a hot air furnace or the like, said device being positioned in the line of the pipe with which it is incorporated, to have heated air pass thru it, said device including a tubular casing connecting portions of said hot air pipe, said casing having a peripheral opening to outside air, a tapered tubular member within said casing, positioned in a transverse plane, which includes said opening, the larger end of said tapered tubu- 75

lar member coinciding with the inner wall of said casing, and positioned to receive an unobstructed flow of air from a portion of said air pipe, the smaller end of said tapered, tubular member being positioned to discharge on unobstructed flow of air into an adjoining and succeeding portion of said air pipe, whereby heated air, passing thru the said tapered, tubular member, at its small end, will flow in a central zone of said succeeding portion of said air pipe, at a materially increased

lineal velocity, and carry along with it, outside air, coming in thru said opening, to flow in a cylindrical body of outside air, surrounding the said central zone of velocity increased, heated air.

4. An air flow device made in accordance with claim 3, having in addition thereto, a radially projecting flange surrounding said casing, and positioned to be to one side of said opening.

JOSEPH RUCIER. 10
